UNITED STATES PATENT OFFICE.

PETER KRUSE, OF BROOKLYN, NEW YORK, ASSIGNOR TO E. W. BLISS COMPANY, OF BROOKLYN, NEW YORK, A CORPORATION OF WEST VIRGINIA.

CAN-END-MARKING ATTACHMENT FOR SEAMING MACHINES OR THE LIKE.

Application filed September 4, 1924. Serial No. 735,853.

To all whom it may concern:

Be it known that I, PETER KRUSE, a citizen of the United States of America, residing in the borough of Brooklyn, county of 5 Kings, city and State of New York, have invented certain new and useful Improvements in Can-End-Marking Attachments for Seaming Machines or the like, of which the following is a specification.

10 This invention relates to improvements in can end marking attachments for seaming machines or the like, and aims to provide improvements therein. The invention provides a simple and compact mechanism 15 adaptable as an attachment to the can end feeding mechanism of seaming machines or the like, and is especially intended as an attachment for the can end feeding mechanism of the Wilson & Sumner seaming machine 20 described in Patents No. 1,203,295, dated October 31, 1916, and No. 1,250,406, dated December 18, 1917. The present attachment may be incorporated in this machine without involving any change in the design or 25 construction thereof, except the substitution of the bracket for supporting the can end feeding mechanism by another bracket provided with bearings for the shafts of the marking attachment.

30 An embodiment of the invention is illustrated in the accompanying drawings.

Referring to said drawings,

Figure 1 is a top plan view of the receiving end of a Wilson & Sumner seaming machine, showing the can end feeding mechanism together with the marking attachment forming the subject-matter of the present improvement;

Fig. 2 is a cross-section on the line 2—2, 40 Fig. 1;

Fig. 3 is a sectional view on the line 3—3, Fig. 2;

Figs. 4 and 5 are detail views of the marking means.

45 Referring to said drawings, numeral 10 designates the marking attachment as a whole, which is conveniently mounted on the same bracket 11 which serves to support the can end magazine 13, from the bottom 50 of which magazine can ends are separated one at a time by suitable means, as a knife 15. Means for separating the can ends from the bottom of the stack in the magazine may be of any suitable construction, being 55 preferably constructed in substantial ac-

cordance with the mechanism shown in Wilson & Sumner Patent No. 1,203,295. From the bottom of the magazine the separated can ends fall into or upon a feed-way 20, the can ends being supported at one side in a groove 22 in a semi-circular notch 23 in a revolving disk or turret 25, and at the other side in an edge groove 27 in a strip 28 concentric with the axis of the shaft 30 on which said disk 25 turns.

60 Numeral 35 designates a station where the cans and can ends are joined, that is, the can ends are placed upon the open ends of the can bodies. The mechanism at station 35 may be of any suitable type, being preferably substantially the same as that shown in Wilson & Sumner Patent No. 1,203,295.

70 The marking attachment 10 is located intermediate the can end magazine and the joining station 35, and the joining station 35 75 and the can end magazine are preferably separated a distance of not more than three notches of said turret 25.

75 The marking attachment consists of two 80 rotary parts 40, 41, turning on axes at right angles to one another. One of these rotary parts, here shown as the part 40, is in the form of a relatively thin disk, mounted upon a vertical shaft 43, and turning in a plane 85 parallel and immediately adjacent to the plane of the feed-way 20. This rotary disk 40 turns immediately under the can ends as they are fed past the same in the feed-way, and turns in the space between the can end and the can body traveling beneath the 90 same, and with it toward the joining station 35.

95 The other rotary part 41 is also preferably in the form of a disk turning on a horizontal shaft 45. The shaft 45 fits in horizontal bearings 47 in the bracket 11, and the vertical shaft fits in vertical bearings 49 also formed upon said bracket.

100 The shaft 45 extends across the feed-way 20, and is preferably geared to the shaft 43 100 by means of bevel gears 50, 51, so that the shaft 45 serves to turn the shaft 43. The shaft 45 is preferably driven from the shaft 30 of the turret 25, as by means of bevel gears 53, 54. The ratio of the gears 53, 54 105 is such in relation to the radius of the disk 40, that the peripheral speed of the disk 40 corresponds to the peripheral speed of the turret 25, that is, of the can ends carried along by said turret, and the peripheral 110

speed of the disks 40 and 41 is preferably the same.

The bracket 11 is provided with a slot or opening 57 therein, which permits the disk 41 to project through the bracket and to make contact with the upper side of a can end fed along beneath the same in the feed-way 20.

The rotary disk 40 is provided with a marking die 60 upon its upper face, as shown in Figs. 4 and 5, and the rotary disk 41 is provided with a corresponding or matching marking die 61 projecting from its periphery, as indicated in Fig. 4.

15 The disks 40 and 41 are close enough together to just permit of the thickness of the metal forming the can end to pass between the marking dies 60, 61, as shown in Fig. 4.

The disks carrying the marking dies are 20 so timed as to come together just as a can end passes between the disks. Consequently, as the can end passes between the marking dies, it will be marked or indented by the dies.

25 The marking dies are preferably readily removable to permit of the substitution of differently marked dies from time to time, during the time that the machine is being used. Conveniently, the marking dies fit in 30 corresponding slots 63, 64, in the disks 40, 41, being held therein by screws 66 or the like.

To prevent uneven or unequal movement of the two disks 40, 41, due to back-lash or 35 looseness in the gears 50, 51, a brake 70 is conveniently provided to act upon the shaft 43, so that said shaft is turned against a constant resistance. The teeth of the gears are 40 thereby held steadily and constantly in contact, and consequently, when the dies 60, 61 are once set so as to match, they will continue to match as they come together during subsequent rotations of said disks.

45 Modification of the structure specifically illustrated and described may be made without departing from the idea of invention.

What is claimed is:

1. A marking attachment for can end feeding mechanism, comprising a feed-way 50 for individual can ends, and a pair of rotary parts turning on axes at right angles to one another, having matching marking dies thereon, one of said rotary parts being a disk turning in a plane parallel to and immediately adjacent the plane in which said can ends travel in said feed-way, said can ends being adapted to pass between said rotary parts and the marking dies thereon.

2. A marking attachment for can end 60 feeding mechanism, comprising a feed-way for individual can ends, a pair of rotary parts turning on axes at right angles to one another, having matching marking dies thereon, one of said rotary parts being a disk 65 turning in a plane parallel to and immedi-

ately adjacent the plane in which said can ends travel in said feed-way, said can ends being adapted to pass between said rotary parts and the marking dies thereon, means for feeding said can ends in said feed-way, and means for turning said rotary parts at the same peripheral speed as the speed at which said ends are fed by said feeding means.

3. A marking attachment for can end 75 feeding mechanism, comprising a feed-way for individual can ends, a pair of rotary parts turning on axes at right angles to one another, having matching marking dies thereon, one of said rotary parts being a disk 80 turning in a plane parallel to and immediately adjacent the plane in which said can ends travel in said feed-way, said can ends being adapted to pass between said rotary parts and the marking dies thereon, means for feeding said can ends in said feed-way, and means for feeding cans beneath said ends, said feed-way being spaced above said cans a distance sufficient to enable said disk to rotate between the can ends in the feed-way and the cans beneath.

4. A marking attachment for can end 85 feeding mechanism, comprising a feed-way for individual can ends, a notched turret for feeding ends in said feed-way, a pair of rotary parts turning on axes at right angles to one another, having matching marking dies thereon, one of said rotary parts being a disk 90 turning in a plane parallel to and immediately adjacent the plane in which said can ends travel in said feed-way, said can ends being adapted to pass between said rotary parts and the marking dies thereon, said axes of said rotary parts being intermediate a can-end magazine and a station where the 95 ends are placed upon a can body, said station and can-end magazine being not more than three notches of said turret apart.

5. A marking attachment for a can-end 100 feeding mechanism, comprising a feed-way 110 for individual can ends, a notched turret for feeding ends in said feed-way, a pair of rotary parts turning on axes at right angles to one another, having matching marking dies thereon, one of said rotary parts being a disk 115 turning in a plane parallel to and immediately adjacent the plane in which said can ends travel in said feed-way, said can ends being adapted to pass between said rotary parts and the marking dies thereon, one 120 of said rotary parts having a shaft crossing said feed-way and gearing with a gear on said turret, and the other rotary part comprising a shaft at one side of said feed-way and gearing with said first-named shaft.

6. A marking attachment for can end 125 feeding mechanism, comprising a feed-way for individual can ends, a notched turret for feeding ends in said feed-way, a pair of rotary parts turning on axes at right angles 130

to one another, having matching marking dies thereon, one of said rotary parts being a disk turning in a plane parallel to and immediately adjacent the plane in which said can ends travel in said feed-way, said can ends being adapted to pass between said rotary parts and the marking dies thereon, said axes of said rotary parts being inter-

mediate a can-end magazine, and a station where the ends are placed upon a can body, and a bracket supporting both said can-end magazine and the parts of said marking attachment. ¹⁰

In witness whereof, I have hereunto signed my name.

PETER KRUSE.
